UNITED STATES PATENT OFFICE.

SVEN J. STRID, OF CHICAGO, ILLINOIS.

MEANS OF SECURING A WOODEN LINING TO A CORRUGATED WALL.

Application filed August 21, 1924. Serial No. 733,344.

To all whom it may concern:

Be it known that I, SVEN J. STRID, residing at Chicago, county of Cook, State of Illinois, and being a citizen of the United States, have invented certain new and useful Improvements in Means of Securing a Wooden Lining to a Corrugated Wall, of which the following is a full, clear, and exact description, such as will enable others skilled in the art to which it appertains to make and to use the same; reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

Corrugated metallic end walls of various types are in general use which comprise metallic plates having corrugations of different configurations formed therein to strengthen and stiffen them. Such ends are made of a plurality of plates with the meeting edges positioned horizontally or vertically and with the corrugations positioned horizontally or vertically. However, the number of plates or position of the corrugations is immaterial to my invention.

It is customary to line such corrugated ends with wooden boards to prevent the grain from sweating and mildewing; secondly, to provide means for blocking the lading; and thirdly, to prevent grain leaks. It is essential that this lining be secured by means which would not permit moisture to enter the car. Nailing strips have been inserted in the corrugations and held thereto by bolts which project through the corrugated end, but experience has shown that moisture and dampness follow this bolt.

It is customary to run the lining boards perpendicular to the direction of the corrugation and it is preferable to allow the running boards to bear against the apices of adjacent corrugations so that the thrust of the shifting lading will be carried directly through the lining board to the corrugation.

This lining must be fastened securely and rigidly to the end wall because the anchoring of the lading and the racking of the car have a tendency to loosen it.

One of the objects of the invention is to securely and rigidly fasten a wooden lining

to a corrugated metallic wall of a railway box car.

In the drawings:

Fig. 1 is a section of a corrugated end wall with my invention applied thereto.

Fig. 2 is an elevation of Fig. 1 taken from the inside of the car with the lining and nail removed.

Fig. 3 is a section of a corrugated end wall with a modification of my invention applied thereto the same being taken along the line 1-1 of Fig. 4 in the direction indicated by the arrows.

Fig. 4 is an elevation of Fig. 3 taken from the inside of the car with the lining and nail removed.

Figs. 5, 6 and 7 show the holder in detail.

In the drawings 1 is a corrugated metallic wall having inwardly projecting apices 2, outwardly projecting apices 3 and lining 4. The fastener 5 is held to the corrugated wall 1 by rivets 6 or other convenient means. The fastener 5 is formed so as to provide adjacent portions 7-8 with the inclined portions 9-10 and curved portion 11. This fastener 5 may be of any desired length. The lining is held against the adjacent apices 2-2 while the nail 12 is driven in place. This nail 12 is guided by surfaces 9 and 10 into the space between portions 7-8 and upon coming in contact with portion 11 the nail is deflected or clinched, as shown at 13, so that it rigidly secures the lining in place.

In the modified form shown in Figs. 3 to 7 inclusive the fastener 20 is secured to the corrugated wall 1 by rivets 21 or any other convenient means. The holder 22 is secured to fastener 20 by bolts 23 (or any other convenient means) through holes 24. The holder 22 is provided with inclined or guiding surfaces 25 so that as the nail 30 is driven in place it is guided by these inclined surfaces 25 and portion 26 of the fastener so that the nail comes in contact with and is deflected by portion 27 of the fastener, thereby forming a hook connection with the holder 22. The fastener 20 or holder 22 may be of any desired length. In this modification the holder is provided with ribs 28 between the guiding surfaces 25, which ribs have inclined surfaces 29. These ribs prevent the nail from bending sidewise.

My device is positioned within the planes bounding the inwardly and outwardly pro-

jecting corrugation so that it permits the lining 4 to bear against the adjacent apices 2 of the corrugations and furthermore does not necessitate any increase in the length 5 of the car. However, my invention is not limited to placing these fasteners within the corrugation.

These fasteners 5 and 20 are preferably applied to the corrugated wall before it is 10 installed on the car.

I claim:

1. In combination with a wall element for a railway car having a plurality of corrugations formed therein, a fastener secured 15 to said wall, a lining, a nail securing said lining to the fastener, said fastener comprising means to guide and deflect the nail as it is driven between adjacent portions of the fastener whereby said nail is retained 20 between said portions.
2. In combination with a wall element for a railway car having a plurality of corrugations formed therein, a fastener secured to said wall within one of said corrugations, 25 a lining touching the apices of adjacent corrugations, a nail securing said lining to the fastener, said fastener comprising means to

guide and deflect the nail as it is driven between adjacent portions of the fastener whereby said nail is retained between said 30 portions.

3. In combination with a wall element for a railway car having a plurality of corrugations formed therein, a fastener secured to said wall, a holder secured to said fastener, a lining, a nail securing said lining to the fastener and holder, said fastener comprising means to guide and deflect the nail as it is driven between the holder and the fastener whereby the nail is retained between 40 said holder and fastener.

4. In combination with a wall element for a railway car having a plurality of corrugations formed therein, a fastener secured to said wall within one of said corrugations, 45 a holder secured to said fastener, a lining touching the apices of adjacent corrugations, a nail securing said lining to the fastener and holder, said fastener comprising means to guide and deflect the nail as 50 it is driven between the holder and the fastener whereby the nail is retained between said holder and fastener.

SVEN J. STRID.
